UNITED STATES PATENT OFFICE.

WILLIAM KENNISH, OF PHILADELPHIA, PENNSYLVANIA, ASSIGNOR TO
CHARLES WIRGMAN AND JOHN M. WIRGMAN, OF SAME PLACE.

IMPROVEMENT IN INSECT-GUNS.

Specification forming part of Letters Patent No. **148,069**, dated March 3, 1874; application filed
August 26, 1873.

To all whom it may concern:

Be it known that I, WILLIAM KENNISH, of the city of Philadelphia, in the State of Pennsylvania, have invented an Insect-Gun, of which the following is a specification:

The object of my invention is to expel, in a fine cloud, pyrethrum, or other powder used for the destruction of insects or other vermin, directly from the bottle or flask in which it is sold.

The accompanying drawing of the machine or gun—as Figures 1 and 2—illustrates my invention.

It consists of a neck, bulb, and collar made of india-rubber or other elastic substance, and a tube made of metal, bone, or other material.

Fig. 1 represents a general outside view of bottle with the gun attached. Fig. 2 is a sectional view of the same.

The bulb A is made of india-rubber or other elastic material, and is used for expelling the powder, pyrethrum, or other substances by com-

pressing said bulb. The tube B is made of metal, bone, or other material suitable for the purpose, and is attached to the bulb A for the purposes of outlet and direction of the powder, and is held in position by the elastic neck D, into which it is inserted. C, Figs. 1 and 2, shows the collar expanded and attached to the neck of the bottle or flask, both the bottle or flask and tube being held in position by the elastic force of the material employed. The bulb A, the collar C, and the neck D are cast in one piece.

I do not claim as my invention the use of an elastic bulb for receiving and expelling powder and other substances; but

I claim—

An insect-powder gun consisting of a collar, C, an elastic bulb, A, and a discharge-pipe, B, substantially of the form and for the purpose specified.

WILLIAM KENNISH.
